UNITED STATES PATENT OFFICE.

AVERY C. BRUCE, OF BIRMINGHAM, ALABAMA, ASSIGNOR TO SENN PRESSED STEEL HOE AND TOOL COMPANY, OF BIRMINGHAM, ALABAMA, A CORPORATION OF ALABAMA.

HOE.

1,148,210.

Specification of Letters Patent. Patented July 27, 1915.

Application filed August 25, 1913. Serial No. 786,557.

To all whom it may concern:

Be it known that I, AVERY C. BRUCE, a citizen of the United States of America, residing at Birmingham, in the county of Jefferson and State of Alabama, have invented 5 certain new and useful Improvements in Hoes, of which the following is a specification.

My invention relates to hoes and like implements and has for its object to improve 10 and perfect the socket portion thereof and to simplify the manner of fastening the handle in the socket.

An important object of my invention is to 15 avoid the use of screws, rivets or bolts as the means for attaching the handle to the shank.

A further object is to provide a split tapering socket which is adapted to receive 20 the wedge shaped lower end of a standard handle and to be clamped about such wedge end by a readily detachable clamp ring.

A further object of my invention is to 25 improve the manner of forming sockets for hoes constructed in accordance with United States Letters Patent to Edward Senn No. 922,202, wherein the socket is formed by twisting and bending a socket portion which is integral with the blade and connected 30 thereto by a neck. According to my invention, the socket portion is formed with tapering outer ends which are shaped and twisted to form a split tapering socket. By providing a notch at the center of the socket 35 portion which forms the heel of the finished socket, I find that, when the socket portion is being twisted and bent, I obtain a more perfect closing up of the joint at the top of the heel between the socket sections, and get 40 a more rounded and satisfactory shape for the heel portion.

I have illustrated my invention, in its preferred embodiments only, in the accompanying drawings which form a part of this 45 specification, and in which:—

Figure 1 is a plan view of the hoe blank. Figs. 2 and 3 show two steps in the shaping of the blank to form the socket. Fig. 4 is

a detail perspective view of the finished hoe shown in Fig. 3. Fig. 5 is a side elevation 50 of the complete hoe showing the manner of fastening the handle in the socket. Figs. 6, 7 and 8 are views corresponding to Figs. 1, 2 and 3 of a double ended hoe.

Similar reference numerals refer to similar parts throughout the drawings.

As illustrated, the hoe blank is stamped or cut from sheet steel or any suitable metal and comprises the blade portion 1, the neck portion 2, and the socket portion 3. The 60 portions 1 and 3 are separated by notches 4, which are separated by the neck portion, and the peculiar shape of these notches forms no part of my present invention. It will be noted that the ends or wings 5 of the 65 socket portion 3 are made tapering from the center toward their ends and that a scroll shaped notch 6 is cut at the center of the top edge of the portion 3 opposite to the neck 2. After the blank has been thus 70 formed, the wings 5 are bent to the position shown in Fig. 2 and a reinforcing rib or corrugation 7 is formed in and extends across the portions 1, 2 and 3. I make no claim to the manner of forming this reinforcement 75 as the same forms no part of my present invention. The socket portion and its wings are then shaped in a die to form the split socket 8, as seen in Fig. 3, the notch 6 permitting the metal, in the center of the 80 portion 3, as it is bent over in the dies to form the heel portion 9 of the socket, to give a close top joint formed by bringing the edges of the notch together. Also by cutting a notch at what would be the upper end 85 of a right angled fold in the blank, I avoid a sharp corner at the top of the heel and provide a more rounded surface which is desirable. The split tapering socket as thus provided is adapted to receive the wedge 90 shaped end 10 of a hoe handle 11, this end being inserted in the socket and then the split sections of the latter are forced together and clamped in that position about the wedge by a ring 12. This ring, by gripping the ends of the socket members to-

95

gether, contracts the open end of the socket to a less diameter than the wedge end of the handle, thereby making it impossible for the latter to pull out or come loose. At the same time, the ring can be readily disengaged and the hoe detached from the handle when desired.

In Figs. 6 to 8 the blank is formed with hoe blades 13 and 14 on each end connected by neck portions 2 with an intermediate socket portion 15 which is provided with tapering wings 16 having converging upper and lower edges. These wings, as seen in Fig. 7, are bent into parallelism in planes at right angles to the blades and then shaped by dies to form a split tapering socket 17 adapted to receive the wedge end of a handle and be fastened thereon by the ring 12 in the manner shown in Fig. 5.

The exact shape of the notch 6 may be modified in various ways, provided sufficient metal is cut away at the center of the top edge of the socket portion so as to provide a smooth rounded heel portion for the socket with a tightly closed joint where the socket portions diverge from the heel portion 9.

As I have heretofore stated, I make no claim in this application to the manner of reinforcing the neck of the hoe by means of the rib 7 nor do I claim the improved construction of the slots 4 which differ from the construction in the Senn patent referred to, which features form the subject matter of an application filed of even date herewith by the said Edward Senn.

Having thus described my invention, what I claim as new and desire to secure by Letters Patent, is:—

1. As an article of manufacture, a hoe comprising a blade and socket portion, the latter being formed by one or more concavo-convex portions which taper toward the open outer end of the socket and which when contracted form a substantially circular socket which is smallest at its open end, and a reinforced inner end for the socket forming an end bearing for the handle.

2. An article of manufacture, a hoe comprising a blade and tubular split socket portion, the socket being adapted, when contracted, to become smaller toward its open end, a handle having an enlarged wedge shaped end adapted to fit into said split socket and against the inner end of the socket, and a clamp ring adapted to be forced on the split end of the socket to contract it about the smaller end of said wedge end of the handle and interlock it and said socket, substantially as described.

3. In a hoe or like tool, an integral blade and socket, the socket being formed by oppositely facing wings which are bent toward each other in the same plane, and

curved in transverse cross sections to jointly form a split tubular socket which, when contracted, becomes smaller toward its open end, a handle having an enlarged wedged end adapted to be inserted into the split socket when in expanded position and to abut against the inner end of the socket, and a slip ring to hold the free ends of the socket wings contracted and clamped tightly about the smaller end of said wedged end of the handle to wedge lock the handle in the socket, substantially as described.

4. In a hoe, a blade, tapering portions integral with the blade and which are bent toward each other and at an angle to the blade and are rounded in cross section to form between them a substantially circular split socket the concave members of which taper toward its open end, a handle having an enlarged wedge end adapted to be inserted in the open end of said socket and to bear against the inner end of the socket, and means to fasten the handle in the socket consisting solely of a clamp ring which is forced over the end of the socket after the handle has been inserted therein to contract the end of the socket sufficiently to positively prevent the withdrawal therefrom of said handle.

5. A hoe comprising a blade and an integral socket portion, the socket portion being formed by wings which are concavo-convex in cross section and which taper longitudinally toward the open end of the socket, said blades when contracted being adapted to abut along their longitudinal edges to form a closed socket in the shape of a truncated cone smallest at its open end and closed at its inner end adjacent to the blade, substantially as described.

6. A hoe comprising integral blade and socket portions, the socket portion being split and shaped to taper toward its open end, when in contracted position about a handle, and form a tubular socket closed except at its open end, and means to retain a handle in said socket consisting of a clamp ring to hold the open end of the socket in contracted position about a handle, substantially as described.

7. A hoe or like tool comprising a blade and an integral tubular split socket closed at its blade end and there reinforced by an indented reinforcing rib, a handle having an enlarged wedge shaped end adapted to be inserted into said socket when in its expanded position and to bear against said rib, and a clamp ring to contract the outer end of said socket about the smaller end of said wedge shaped end of the handle to wedge lock the parts.

8. A hoe or like tool formed from an integral blank having a blade portion, a neck and a socket portion, the socket portion be-

ing bent to form a tubular split socket closed at its inner end and when contracted being reduced in diameter toward its open end, a reinforced indented rib which 5 extends across the neck and to the axis of the socket, an enlarged handle end adapted to enter the socket and bear against said rib, and a clamp ring to contract the socket

about the smaller part of said enlarged handle end to wedge lock it to the tool.

In testimony whereof I affix my signature in presence of two witnesses.

AVERY C. BRUCE.
